[57] CLAIM

The ornamental design for a door mat base plate or similar article, as shown and described.

DESCRIPTION

FIG. 1 is a top plan view of a door mat base plate or similar article showing our new design;

FIG. 2 is a front elevational view thereof;

FIG. 3 is a bottom plan view thereof;

FIG. 4 is a left side elevational view thereof;

FIG. 5 is a rear elevational view thereof;

FIG. 6 is a larger scale fragmentary sectional view thereof, taken along line 6—6 in FIG. 1;

FIG. 7 is a fragmentary sectional view thereof, on the same scale as FIG. 6, taken along line 7—7 in FIG. 1; and

FIG. 8 is a fragmentary sectional view thereof, on the same scale as FIG. 6, taken along line 8—8 in FIG. 1.
